UNITED STATES PATENT OFFICE

113,690

DESIGN FOR A COSMETIC SPREADING ROLLER

Paul Tresenberg, New York, N. Y.

Application December 6, 1938, Serial No. 81,606

Term of patent 3½ years

To all whom it may concern:

Be it known that I, Paul Tresenberg, a citizen of the United States, residing at Queens, New York city, county of Queens, State of New York, have invented a new, original, and ornamental Design for a Cosmetic Spreading Roller, of which the following is a specification, reference being had to the accompanying drawing, forming part thereof.

In the drawing,

The figure is a perspective view of a cosmetic spreading roller showing my new design.

I claim:

The ornamental design for a cosmetic spreading roller, as shown.

PAUL TRESENBERG.
